ABSTRACT

A hybrid rotary drill bit having at least one fixed blade and at least one rolling cutter assembly is configured for reverse fluid flow from an annulus, through junk slots and into a fluid pathway system located substantially centrally to a bit body. The fluid pathway system may be located underneath a portion of the at least one fixed blade.

REVERSE CIRCULATION HYBRID BIT

CROSS-REFERENCE TO RELATED APPLICATION

This application claims priority to and benefit of U.S. Provisional Application Ser. No. 62/066,324, filed on Oct. 20, 2014, the contents of which are incorporated herein by reference for all purposes.

BACKGROUND OF THE INVENTION

Field of the Invention

The embodiments disclosed and taught herein relates generally to hybrid drill bits having at least one fixed blade and at least one rolling cutter assembly and, more specifically, relates to a hybrid drill bit configured for reverse circulation.

Description of the Related Art

Rotary earth-boring bits useful for oil and gas exploration and production have evolved considerably since the bi-cone bit developed by Howard R. Hughes, Sr., which had two rotatable cone-shaped cutting elements. Today, there are rotary bits with fixed or non-rotating blades with polycrystalline diamond cutters (PDC) mounted thereon. There are also rotary hybrid drill bits combining fixed-blade cutting elements and rotating cutting elements. Most, but not all hybrid bits are modular in construction, in that the rotatable or rolling cutter elements are separate components coupled to the bit body by welding or other type of fastening.

Usually, the cuttings from the bottom and sides of the borehole are removed by drilling fluid (a liquid) that is pumped downhole from the surface. The cuttings are entrained in the fluid and carried by the drilling fluid to the surface for removal and disposal. Typically, the circulation path involves pumping drilling fluid down the hollow center pipe or drill string, forcing the fluid through jets or orifices in the drill bit to wash away the cuttings, and returning the cuttings-laden fluid to the surface through the annulus.

It is also known to use a "reverse" circulation path in which the drilling fluid is pumped down the annulus to the drill bit where the cuttings are entrained in the fluid and the fluid is returned to the surface through the hollow drill pipe. Reverse circulation requires that the drill bit be configured specifically to allow the cuttings-laden fluid to pass through to the drill pipe. While reverse circulation has been used successfully with rotating cutter rotary bits, configuring a fixed-blade bit or hybrid bit for reverse circulation presents numerous issues not present in rotating cutter rotary bits, which issues have not heretofore been overcome.

The embodiments disclosed and taught herein is directed to an improved modular hybrid bit configured for reverse circulation.

BRIEF SUMMARY OF THE INVENTION

As a brief summary of one of the many embodiments of the present disclosures, a hybrid drill bit may comprise a body having at least one blade, each blade comprising a plurality of earth formation cutting elements; at least one rolling cutter assembly having a head onto which a cutter element is rotatably coupled; and a reverse circulation system adjacent a lower portion of the bit body and is

2

configured to allow cuttings to pass therethrough and configured to maximize the load bearing capacity of the bit.

Other and further summaries of the disclosure are presented in the drawings, the text and the appended claims.

5 BRIEF DESCRIPTION OF THE DRAWINGS

The following figures form part of the present specification and are included to demonstrate further certain aspects 10 of the present disclosure. The disclosure may be better understood by reference to one or more of these figures in combination with the detailed description of specific embodiments presented herein.

FIG. 1 illustrates an end view of a typical hybrid rotary 15 drill bit configured for conventional, or forward, circulation.

FIG. 2 illustrates a hybrid rotary drill bit configured for reverse circulation according to the present disclosure.

FIG. 3 illustrates another possible embodiment of a 20 hybrid rotary drill bit configured for reverse circulation according to the present disclosure.

FIG. 4 illustrates another possible embodiment of a hybrid rotary drill bit configured for reverse circulation according to the present disclosure.

FIG. 5 illustrates another possible embodiment of a 25 hybrid rotary drill bit configured for reverse circulation according to the present disclosure.

FIG. 6 illustrates another possible embodiment of a hybrid rotary drill bit configured for reverse circulation according to the present disclosure.

30 While the embodiments disclosed herein is susceptible to various modifications and alternative forms, only a few specific embodiments have been shown by way of example in the drawings and are described in detail below. The figures and detailed descriptions of these specific embodiments are not intended to limit the breadth or scope of the inventive concepts or the appended claims in any manner. Rather, the figures and detailed written descriptions are provided to illustrate the inventive concepts to a person of ordinary skill in the art and to enable such person to make 40 and use the inventive concepts.

DETAILED DESCRIPTION

The figures described above and the written description of 45 specific structures and functions below are not presented to limit the scope of what Applicants have invented or the scope of the appended claims. Rather, the figures and written description are provided to teach any person skilled in the art to make and use the disclosures for which patent protection 50 is sought. Those skilled in the art will appreciate that not all features of a commercial embodiment of the disclosures are described or shown for the sake of clarity and understanding. Persons of skill in this art will also appreciate that the development of an actual commercial embodiment incorporating 55 aspects of the present disclosures will require numerous implementation-specific decisions to achieve the developer's ultimate goal for the commercial embodiment. Such implementation-specific decisions may include, and likely are not limited to, compliance with system-related, business-related, government-related and other constraints, which 60 may vary by specific implementation, location and from time to time. While a developer's efforts might be complex and time-consuming in an absolute sense, such efforts would be, nevertheless, a routine undertaking for those of skill in this art having benefit of this disclosure. It must be understood that the embodiments disclosed and taught herein is 65 susceptible to numerous and various modifications and

alternative forms. Lastly, the use of a singular term, such as, but not limited to, "a," is not intended as limiting of the number of items. Also, the use of relational terms, such as, but not limited to, "top," "bottom," "left," "right," "upper," "lower," "down," "up," "side," and the like, are used in the written description for clarity in specific reference to the figures and are not intended to limit the scope of the disclosure or the appended claims.

Embodiments of the present disclosure include a hybrid drill bit comprising a single or a plurality of fixed blades, at least one of which comprises a cutting element, and a single or a plurality of rolling cutter assemblies, at least one of which comprises a cutting element. A fluid pathway system adjacent the longitudinal axis of the bit is configured and provided to allow drilling cuttings to flow from the borehole through the fluid pathway system and into the drill pipe. The fluid pathway system may comprise a single, centralized opening, such as a circle or an ellipse in cross section. Alternatively, the fluid pathway system may comprise a plurality of openings of undetermined or determined shape, located on or about the longitudinal axis. In any of the embodiments, the opening(s) may be substantially planar (i.e., substantially two-dimensional) or three-dimensional, in that the opening(s) may have a longitudinal aspect to its shape. As taught herein, the fluid pathway systems may be designed and implemented in such fashion to maximize both the load bearing capacity of the drill bit and the flow area of the fluid pathway system. It will be appreciated that with this disclosure, fluid flow comes from the surrounding annulus, washes through the junk slots and enters the fluid pathway system on its way to the surface. The transition between the junk slots and the fluid pathway system may comprise hardfacing or other material systems configured to provide erosion resistance.

Turning now to FIG. 1, illustrated is a hybrid rotary drill bit 100 configured for forward circulation. Drill bit 100 may comprise a fixed blade 102 and a rolling cutter assembly 104. As illustrated in FIG. 1, the drill bit 100 has three fixed blades 102 and three rolling cutter assemblies 104. Fixed blade 102 may have at least one and preferably multiple cutting elements 106. Similarly, the rolling cutter assembly 104 may have at least one and preferably multiple cutting elements 108. It will be appreciated that the term "cutting element" is used, even though the process by which formation material is removed is not technically by "cutting." Cutting elements 106 and 108 comprise all those elements known in the art to aid the removal of formation material regardless of the process used including, but not limited to, cutting, shearing and crushing processes. Because drill bit 100 is configured for forward circulation, drill bit 100 comprises one or more fluid nozzles 110 and one or more fluid ports 116 adapted to allow drilling fluid (not shown) to pass therethrough and wash away drilling cuttings. FIG. 1 illustrates nozzles 110, 112 and 114 and ports 116, 118 and 120. For example, three ports are shown, each having a diameter of about $\frac{7}{16}$ of an inch (about 0.15 in²). Three nozzles are also shown, each having a diameter of about $\frac{5}{16}$ of an inch (about 0.31 in²).

FIG. 2 illustrates a hybrid rotary drill bit 200 configured according to the present disclosure for reverse circulation. The drill bit 200 comprises at least one fixed blade 202 on which at least one cutting element 206, preferably, is located. The drill bit 200 also comprises at least one rolling cutter assembly 204, which preferably comprises at least one cutting element 208. Comparing drill bit 100 in FIG. 1 to drill bit 200 in FIG. 2, drill bit 200 does not utilize fluid nozzles 110 or fluid ports 116. Instead, drill bit 200 com-

prises a reverse circulation fluid pathway system 250, which in this embodiment preferably comprises a substantially round and substantially planar opening in the bit body substantially centered about the longitudinal axis of the bit 200. As an example of a particular embodiment, for a nominal 10-inch diameter drill bit, the fluid pathway system 250 may comprise an opening having an effective or average diameter of about 3 inches. Alternatively, the fluid pathway system 250 may have a cross-sectional area substantially the same as or larger than the drill bit shank bore (not shown). It will be appreciated that the fluid pathway system 250 is defined underneath the junction of the fixed blades 202. In other words, a portion of the fixed blades 202 adjacent the longitudinal axis may be cantilevered over the fluid pathway system 250.

FIG. 3 illustrates another hybrid rotary drill bit 300 configured according to the present disclosure for reverse circulation. The drill bit 300 comprises at least one fixed blade 202 on which at least one cutting element 206, preferably, is located. The drill bit 300 also comprises at least one rolling cutter assembly 204, which preferably comprises at least one cutting element 208. Drill bit 300 comprises a reverse circulation fluid pathway system 350 comprising three slots 350a, 350b and 350c. Each of these portions may have a slot-like shape as illustrated, and in the embodiment illustrated in FIG. 3 are approximately 1 inch wide by about 2 inches long. Unlike the drill bit illustrated in FIG. 2, the drill bit of FIG. 3 provides blade 202 support at the bit center 322. It will be understood that fluid pathway slots 350a, 350b and 350c converge into fluid communication with each other and with the bit shank bore (not shown) inside the bit body.

FIG. 4 illustrates yet another a hybrid rotary drill bit 400 configured according to the present disclosure for reverse circulation. The drill bit 400 comprises at least one fixed blade 202 on which at least one cutting element 206, preferably, is located. The drill bit 400 also comprises at least one rolling cutter assembly 204, which preferably comprises at least one cutting element 208. Drill bit 400 comprises a reverse circulation fluid pathway system 450 comprising a substantially round and planar opening, similar to fluid pathway system 250 in FIG. 2. However, the fluid pathway system 450 comprises a replaceable insert 452 adapted to resist erosive wear of the cuttings-laden fluid passing therethrough. As with the drill bit 200 illustrated in FIG. 2, the cross-sectional area of the fluid pathway system 450 is substantially equal to or greater than the cross-sectional area of the bit bore shank.

FIG. 5 illustrates a hybrid rotary drill bit 500 configured according to the present disclosure for reverse circulation. The drill bit 500 comprises at least one fixed blade 202 on which at least one cutting element 206, preferably, is located. The drill bit 500 also comprises at least one rolling cutter assembly 204, which preferably comprises at least one cutting element 208. Drill bit 500 comprises a reverse circulation fluid pathway system 550 comprising a substantially centralized opening, such as described for drill bit 200 in FIG. 2. In FIG. 5, one of the rolling cutter assemblies has been removed to show that portion 550a of fluid pathway system 550. In this view, junk slots 560 and 562 are readily visualized. This view also shows how fixed blades 202 may be configured to both maximize the reverse circulation flow area and maximize blade strength.

FIG. 6 illustrates a hybrid rotary drill bit 600 configured according to the present disclosure for reverse circulation. The drill bit 600 comprises at least one fixed blade 202 on which at least one cutting element 206, preferably, is

located. The drill bit 600 also comprises at least one rolling cutter assembly 204, which preferably comprises at least one cutting element 208. Drill bit 600 comprises a reverse circulation fluid pathway system 650 comprising a substantially centralized opening, such as described for drill bit 200 in FIG. 2. In FIG. 6, one of the rolling cutter assemblies has been displaced to show that portion 650a of fluid pathway system 650. In this view, junk slots 660, 662 and 664 are seen. As can be appreciated from this FIG. 6 and FIGS. 2-5 the hybrid bit of this disclosure may utilize modules, such as removable rolling cutter assemblies 204. Also, the materials from which the bit body may be constructed can include steel, matrix materials and combinations.

All of the many possible embodiments of the disclosure described herein may comprise modular rolling cutter assemblies that may be affixed to the bit body by mechanical fasteners, such as bolts or studs and nuts, or by chemical or metallurgical means, such as welding, brazing or amorphous diffusion bonding, or a combination of such systems. Further, embodiments may comprise fixed blades having cutting elements arranged to remove formation material adjacent the bit centerline, and/or arranged to remove formation material from a cone region to a gage region of the bit. The rolling cutter assemblies may be truncated in length and position such that the rolling cutter assemblies do not have cutting elements arranged to remove formation material in the cone and nose regions. The overlay of cutting elements of the fixed blades and the rolling cutter assemblies provide a substantially continuous cutting profile from cone to gage.

Other and further embodiments utilizing one or more aspects of the disclosure described above can be devised without departing from the spirit of disclosure. Further, the various methods and embodiments of the methods of manufacture and assembly of the system, as well as location specifications, can be included in combination with each other to produce variations of the disclosed methods and embodiments. For example, although the embodiments illustrated herein are symmetrical in that each bit has the same number of fixed-blades as rolling cutter assemblies, the disclosure contemplates an asymmetrical arrangement of fixed and rolling cutter assemblies. Discussion of singular elements can include plural elements and vice-versa.

The order of steps can occur in a variety of sequences unless otherwise specifically limited. The various steps described herein can be combined with other steps, interlined with the stated steps, and/or split into multiple steps. Similarly, elements have been described functionally and can be embodied as separate components or can be combined into components having multiple functions.

The disclosures have been described in the context of preferred and other embodiments and not every embodiment of the disclosure has been described.

Obvious modifications and alterations to the described embodiments are available to those of ordinary skill in the art. The disclosed and undisclosed embodiments are not intended to limit or restrict the scope or applicability of the disclosure conceived of by the Applicants, but rather, in conformity with the patent laws, Applicants intend to fully protect all such modifications and improvements that come within the scope or range of equivalent of the following claims.

What is claimed is:

1. A hybrid drill bit comprising:
a bit body having a shank portion and at least three fixed blades;

the shank portion having a fluid bore of a predetermined cross-sectional area extending along a longitudinal axis of the shank portion;

the at least three fixed blades each comprising at least one cutting element configured to remove formation material;

the bit body having at least one rolling cutter assembly disposed adjacent the at least three fixed blades and comprising at least one cutting element configured to remove formation material;

at least one junk slot defined between at least one of the at least three fixed blades and the at least one rolling cutter assembly;

a reverse circulation fluid pathway system to allow for reverse fluid flow without utilizing any nozzles comprising a fluid flow pathway extending from the fluid bore of the shank portion to a single opening in a lower surface of the bit body, the lower surface being located axially at an interface of the at least three fixed blades and a remainder of the bit body,

wherein the single opening is substantially centered on or about a longitudinal axis of the bit;

wherein the lower surface is at least substantially planar at and proximate an outer peripheral edge of the single opening; and

wherein the at least three blades meet and are connected at a point centered on a longitudinal axis of the bit, and wherein each of the at least three blades is partially suspended over the single opening.

2. The hybrid drill bit of claim 1, wherein the at least one rolling cutter assembly comprises three rolling cutter assemblies.

3. The hybrid drill bit of claim 2, further wherein each of the rolling cutter assemblies are truncated such that each rolling cutter is configured to not extend into nose and cone regions.

4. The hybrid drill bit of claim 3, wherein the rolling cutter assemblies comprise a plurality of cutting elements configured to remove formation material from shoulder and gage regions, but not from the nose and cone regions.

5. The hybrid drill bit of claim 4, wherein the at least three fixed blades comprise a plurality of cutting elements configured to remove formation material from a cone region to a gage region.

6. The hybrid drill bit of claim 5, wherein the at least three fixed blades are configured with at least one cutting element configured to remove formation material adjacent a centerline of the bit.

7. The hybrid drill bit of claim 1, wherein the single opening comprises a substantially circular opening.

8. The hybrid drill bit of claim 7, wherein a wall defining the single opening comprises hardfacing to resist fluid erosion.

9. The hybrid drill bit of claim 7, wherein a wall defining the single opening comprises an erosion-resistant insert.

10. The hybrid drill bit of claim 1, wherein the single opening is at least partially located between at least one fixed blade of the at least three fixed blades and the at least one rolling cutter assembly.

11. A method of drilling a subterranean borehole comprising:

running in the borehole a reverse circulation hybrid drill bit;

pumping a drilling fluid to the bottom of the borehole through an annulus formed between a drill string and the borehole;

establishing fluid circulation between the annulus and an interior of the drill string through the drill bit; rotating the drill bit to remove formation material; circulating the removed formation material from the bore-hole bottom, through the drill bit and into the interior of the drill string; and

wherein the hybrid drill bit comprises:

a bit body having a shank portion and at least three fixed blades;

the shank portion having a fluid bore of a predetermined cross-sectional area extending along a longitudinal axis of the shank portion;

the at least three fixed blades each comprising at least one cutting element configured to remove formation material;

the bit body having at least one rolling cutter assembly disposed adjacent at least one of the at least three fixed blades and comprising at least one cutting element configured to remove formation material;

at least one junk slot defined between at least one of the at least three fixed blades and the at least one rolling cutter assembly; and

a reverse circulation fluid pathway system to allow for reverse fluid flow without utilizing any nozzles comprising a fluid flow pathway extending from the fluid bore of the shank portion to a single opening in a lower surface of the bit body, the lower surface being located axially at an interface of the at least three fixed blades and a remainder of the bit body,

wherein the single opening is substantially centered on or about a longitudinal axis of the bit,

wherein the lower surface is at least substantially planar at and proximate an outer peripheral edge of the single opening, and

wherein the at least three blades meet and are connected at a point centered on the longitudinal axis of the bit, and wherein each of the at least three blades is partially suspended over the single opening.

12. A hybrid drill bit comprising:
- a body comprising a shank portion and at least three fixed blades;
- a fluid bore extending through the shank portion of the body and along a longitudinal axis of the body;
- a reverse circulation fluid pathway system to allow for reverse fluid flow without utilizing any nozzles or comprising a fluid flow pathway extending from the fluid bore to a single opening in a lower surface of the body, the lower surface being located axially at an interface of the at least three blades and a remainder of the body, and
- wherein the at least three fixed blades meet and are connected at a point centered on the longitudinal axis of the body, and wherein each of the at least three blades is partially suspended over the single opening.

13. The hybrid drill bit of claim 12, wherein the single opening comprises a variable radius along a circumference of the single opening.

14. The hybrid drill bit of claim 12, further comprising a plurality of rolling cutter assemblies coupled to the body, each rolling cutting assembly being disposed between adjacent blades of the at least three fixed blades.

15. The hybrid drill bit of claim 12, wherein a wall defining the single opening comprises hardfacing to resist fluid erosion.

16. The hybrid drill bit of claim 12, wherein a wall defining the single opening comprises an erosion-resistant insert.
